UNITED STATES PATENT OFFICE.

FRANK ALLEN AND FRANK A. GRATER, OF PROVIDENCE, RHODE ISLAND,
ASSIGNORS TO AMERICAN SHIP WINDLASS COMPANY, OF SAME PLACE.

CAPSTAN.

SPECIFICATION forming part of Letters Patent No. 231,949, dated September 7, 1880.

Application filed December 10, 1879.

To all whom it may concern:

Be it known that we, FRANK ALLEN and FRANK A. GRATER, both of the city and county of Providence, and State of Rhode Island, have invented a new and useful Improvement in Capstans; and we hereby declare that the following is a full, clear, and exact description of the same, reference being had to the accompanying drawings, forming part of this specification.

This invention has reference to an improvement in capstans arranged to be driven by cranks and gears; and it consists in the peculiar and novel arrangement by which the capstan can be driven at a high or low speed, and consequently with increased power when at low speed, as hereinafter specified and claimed.

Figure 1 is an elevation, showing the capstan one-half in side view and one-half in vertical section. Fig. 2 is a top view below the plane of line $x\ x$, Fig. 1, showing the crank-shaft provided with a bevel-pinion gearing into a horizontal gear, forming part of a plate turning on the central shaft or spindle. Fig. 3 is a bottom-plan view of the parts shown in Fig. 2. Fig. 4 is a plan view of the upper end of the capstan-barrel and the compound gear placed within the barrel, showing the ratchet-teeth in the barrel, with which the pawls of the driving-disk engage so as to drive the capstan-barrel directly, and also the ratchet-teeth in the central driving-pinion, by which the capstan is driven with increased power. Fig. 5 is a view of the bracket on which the intermediate or idle gears of the compound gear are supported and firmly secured to the central shaft or spindle. Fig. 6 is a perspective view, and Fig. 7 a sectional view on the plane of line $y\ y$, Fig. 3, of one of the pawls.

The capstan on board of a ship has to be used for various purposes, in some of which it is important to exert the greatest possible power, while in others a rapid revolution of the barrel is required.

If the anchor is to be hoisted, the slack of the chain must first be hauled in, and this should be done as quickly as possible; but when the anchor itself is reached and must be drawn from the earth a much greater power is required.

To facilitate these operations various devices have heretofore been used, the most usual being a compound gear, in which a disk carrying idle-gears is arranged so as to be locked and unlocked, and thus the power increased. In all such devices locking blocks or keys had to be used in stormy cold weather and a rough sea. The locking and unlocking is an operation requiring strength and judgment, and in winter the blocks or keys, or the holes into which they are to be inserted, are liable to obstruction by ice.

To avoid all this, and to construct a capstan that can be operated either at slow or fast speed, with ordinary or increased power, and instantly changed from one to the other, as well as to protect all parts from rain, frost, or the waves, is the object of this invention.

In the drawings, Δ is the base of the capstan, which is firmly secured to the deck by bolts. The base is provided with the central boss, b' , supported on the plate a' , and strengthened by the radial ribs a^2 , usually six. By this arrangement a long central sleeve is provided, into which the central shaft or spindle, B , can be rigidly secured, and thus a firm foundation for the capstan is provided. The shaft or spindle B is stationary, and receives the barrel C , which is provided with two bearings surrounding the spindle B . The one, c' , at the lower end of the barrel rests on the central boss, b' , and supports the weight of the barrel. The upper bearing, c , surrounds the spindle near the center of the barrel, and serves to stay the upper end of the barrel and to support the fixed bracket and the operating mechanism at a point above the base and out of the plane of strain, whereby it is removed from liability to derangement.

The barrel is free to revolve on the spindle to the right, only being restrained by the pawls d , which hold the barrel against any strain in the opposite direction and hold the same in the position desired.

The spindle B varies in thickness, the portion 6 being of less diameter than the portion 5, so that a shoulder is formed by which the spindle rests on the boss b' , and thus adds to the solidity of the structure.

The portion 4 is of less diameter than por-

tion 5, portion 3 less than portion 4, and portion 2 of the smallest diameter. By this arrangement all the parts can be successively placed on the spindle and have a firm bearing on a shoulder of the same. Thus the size of the spindle diminishes upward, and the greatest strength is secured where the barrel bears against the spindle and where the greatest strength is required.

10 D is the capstan-head. This head is firmly secured to the spindle B, and therefore the base A, spindle B, and capstan-head D are fixed parts of the capstan, while the barrel C revolves. On two opposite sides of the cap-

15 stan-head bearings are formed for the horizontal shaft e, which passes through the capstan-head and through the spindle B at 2. The beveled pinion e' gears into the large bevel-gear f' on the horizontal disk F. The shaft e 20 is provided with suitable ends, to which the cranks e² can be readily secured.

In the drawings square projecting ends on which the cranks can be placed are shown; but other means for readily securing the cranks 25 may be resorted to.

The disk F is provided with two sets of pawls. The two pawls f², at or near the periphery of the disk, are beveled so that they will engage with the ratchets f³ on the upper 30 end of the capstan-barrel C when the disk F is turning to the right or with the sun, but will slide over the ratchet f³ when the disk F is turning in the opposite direction. When, therefore, the cranks e² are turned so as to

35 turn by means of the beveled pinion e', the disk F with the sun or to the right, then the capstan-barrel C will be turned in the same direction as the driving-disk F and at the same speed. When it is now desired to turn the

40 capstan-barrel still in the same direction, but with increased power, or when it is found that the men at the cranks cannot overcome the resistance, then, by turning the cranks in the opposite direction, and thereby turning the driving-disk F also in the opposite direction, the pawls f⁴, which are beveled in the opposite direction from the pawls f², will enter the circular ratchet f⁵, the teeth of which are also beveled in the opposite direction from the

45 teeth of the ratchet f³ on the capstan-barrel, and as the ratchet f⁵ is connected with the loose pinion g, the driving-disk F and pinion g will turn together, and the pawls f² will slide over the ratchet on the end of the barrel.

55 The pinion g gears into the idle-gears g', and as these idle-gears are turning on pins secured in the bracket h, (shown in Fig. 5,) and this bracket is firmly secured, by means of a key or otherwise, to the central spindle, B, their

60 motion is transmitted to the toothed rim g² on the capstan-barrel, and the capstan-barrel is driven with an increased power equal to the difference in the diameter between the pinion g and the toothed rim g², which in the drawings is as one to three, and therefore the power

is increased threefold, and as the idle-gears are interposed between the pinion g and the rim g², the motion of the barrel will be always in the same direction, no matter in what direction the cranks are turned; but the power exerted will depend on the direction in which the cranks are turned.

The pawls are provided with stops i, fitting in recesses in sockets in the disk F, (see Fig. 7,) by which they are secured when the capstan is put together, and prevented from jumping out of their place when the capstan is quickly operated, or being displaced from any other cause.

By the construction of the base and the central shaft or spindle great strength is secured in the capstan, and particularly at the place where the greatest strength is required. The various parts can be readily put together or taken apart, and all the parts are secured together and rigidly retained in their place by the central spindle. All the moving parts are above the point where the strain is exerted, and are not liable to be injured by such strain, as is the case in capstans in which the compound gear is placed near the base.

80 The capstan is strong and yet light. No capstan-bars are required and no capstan-bar sockets. It has a smooth exterior and gives perfect protection to the internal gears against 85 water, frost, and dust.

The pawls act by gravitation only, and cannot get out of order, and can be changed automatically from a slow to a fast capstan, or vice versa, by simply reversing the motion of the cranks.

90 The mechanism herein shown and not claimed is embodied in another application for a patent for a similar invention, filed December 31, 1879.

Having thus described our invention, we claim as new and desire to secure by Letters 105 Patent—

1. In a crank-capstan, the combination, with the driving-shaft provided with a beveled pinion and a disk provided with a bevel-gear, of pawls and ratchets arranged to connect the disk with the capstan-barrel directly or through a compound gear, substantially as and for the purpose set forth.

2. The combination, with a capstan-barrel provided with a toothed rim, the driving-shaft, 115 its beveled pinion, and a disk and its bevel-gear, of one or more idle-gears the axes of which are permanently fixed in one position, a pinion provided with a ratchet-gear, and pawls arranged to connect the pinion with the driving mechanism and drive the barrel with increased power or disconnect the same, substantially as and for the purpose set forth.

3. In a capstan, the barrel and its spindle B, idle-gears, and a fixed bracket to receive the 125 said idle-gears, a central pinion, and pawl-and-ratchet mechanism, in combination with an upper bearing, e², to stay the upper end of the barrel and to support the fixed bracket, and the above-described operating mechanism at 130

- a point above the base and out of the plane of strain, whereby the said operating mechanism is removed from liability to derangement, substantially as described.
- 5 4. The combination, with the driving-shaft *e*, the beveled pinion *e'*, the disk *F*, provided with the gear *f'*, the pawl *f²*, and the barrel provided with the ratchet *f³* and the toothed rim *g²*, of the pawl *f⁴*, the pinion *g*, provided with the ratchet *f⁵*, and the idle-gears *g'*, constructed so as to drive the capstan-barrel, as and for the purpose set forth.
- 10 5. The combination, with the driving-disk *F*, provided with sockets to receive the pawls *f²* and *f⁴*, of the pawls provided with the stops *i*, substantially as and for the purpose set forth. 15
